(57) **CLAIM**

The ornamental design for an electric razor, as shown and described.

DESCRIPTION

FIG. 1 is a perspective view of an electric razor showing the new design.

FIG. 2 is a front elevational view thereof.

FIG. 3 is a rear elevational view thereof.

FIG. 4 is an enlarged left side elevational view thereof.

FIG. 5 is an enlarged right side elevational view thereof.

FIG. 6 is a top plan view thereof.

FIG. 7 is a bottom plan view thereof.

FIG. 8 is a front elevational view thereof illustrating the head of the electric razor is movable within a range; and, FIG. 9 is a sectional view thereof, taken along line 9—9 of FIG. 2 and omitting the interior construction.

The broken lines are shown for illustrative purposes only and form no part of the claimed design.
